Henry J. Farrel, Jr. Attorney

UNITED STATES PATENT OFFICE.

FRANKLIN FARREL, JR., OF NEW HAVEN, CONNECTICUT, ASSIGNOR TO FARREL FOUNDRY & MACHINE COMPANY, OF ANSONIA, CONNECTICUT.

CANE-GRINDING MILL.

Application filed May 2, 1921. Serial No. 465,958.

This invention relates to cane grinding machinery such as employed for the extraction of juice from sugar cane, and it has more particular application to mills or 5 grinding apparatus of the type set forth in my application, Serial No. 445,527, filed February 16th, 1921, of which the present application is a continuation in part.

In some of its aspects the invention is especially applicable to cane grinding mills in which one or more three-roll juice expressing mills having a top roll, a cane roll and a bagasse roll, are preceded by a preliminary crusher having one or more pairs of rolls 10 which crush the cane before it reaches said three-roll mill or mills.

In other aspects the invention concerns particularly the construction and operation of a three-roll grinding mill.

One of the objects of the invention is to increase the extraction of juice in a mill without commensurately increasing the area of roll surface employed.

More specifically, my object is to increase the shredding of the cane stalks in the mill so that the stalks will be more finely divided than heretofore, and will form a mat of fine fibers from which the juice may be more readily expressed as the cane moves through the mill than has been possible heretofore.

Another purpose of the invention is to provide a three-roll juice expressing mill with a differential drive which produces a friction motion on the cane and thereby increases the shredding action on the latter.

Another object of the invention is to furnish an improved grinding mill having one or more three-roll juice expressing mills and one or more pairs of preliminary crusher rolls.

To these and other ends the invention consists in the novel features and combinations of parts to be hereinafter described and claimed.

In the accompanying drawing:

Fig. 1 is a fragmentary side elevation, partly in section, of a cane mill embodying my improvements;

Fig. 2 is a fragmentary side elevation showing the roll driving gears;

Fig. 3 is a view similar to Fig. 1, showing a modified form;

Fig. 4 is a fragmentary sectional view showing the grooving and spacing of the

rolls of the three-roll mill illustrated in Fig. 1.

Fig. 5 is a detail elevation of one of the preliminary crusher rolls.

In the mill shown in Fig. 1, I have shown a preliminary crusher A, in front of a juice expressing mill B. The crusher comprises a pair of toothed rolls 10, mounted in a stand or housing 11. There may be two or more pairs of preliminary crushing rolls if desired, but in the particular embodiment now under discussion it may be assumed for purposes of description, that the raw cane as it comes from the field is delivered to the single pair of crushing rolls 10 by a suitable conveyor and chute (not shown). The cane is drawn in and crushed by the rolls 10, so as to split open the stalks and separate the fibers, and the stalks then pass directly to the mill B, consisting of the rolls 12, 13 and 14. The cane moves from the crusher to the mill B over the ordinary inclined bed, which I have not deemed it necessary to illustrate, and enters between the rolls 12 and 13, which are termed the top roll and cane roll respectively. These rolls crush and express a portion of the juice from the cane, which as it leaves them is deflected upwardly in the customary manner by the well known turn plate 15, so as to pass between the top roll and the bagasse roll 14. It may be assumed for purposes of description also, although not necessarily so, that the installation is a large one, capable of handling many tons of cane daily, and that the mill B is followed by a plurality of similar juice expressing mills (not shown), there being suitable conveyors or carriers (not shown) between the several juice expressing mills, in accordance with the usual practice.

The crushing rolls 10 may be of any approved type but preferably they will be provided with annular grooves, and with longitudinal grooves forming in connection with the annular grooves, teeth for hooking or drawing in the cane so that the latter will be fed into the machine uniformly and expeditiously. A suitable roll for the purpose is shown in Fig. 5 and is described in detail in my application, Serial No. 445,527, previously mentioned. It has a plurality of circumferential grooves 10^a and a plurality of generally longitudinal grooves 10^b . The circumferential grooves of each crusher roll

mesh with those of the other roll, and the grooves 10^b form interruptions in the circumferential grooves and create teeth that are adapted to hook or draw in the cane.

With the purpose of increasing the shredding effect of the rolls, both of the preliminary crusher, and three-roll mill, and of augmenting the capacity of the machine, a differential motion of one roll relatively to its mate or coacting roll is provided. One roll rotates at a materially greater surface speed than the roll on the opposite side of the cane stalk. The result is that the cane stalks are torn apart more thoroughly and more effectively shredded and opened up so as to separate the individual fibers of the cane to a considerable degree; and by shredding the cane in this manner the fibers are put in a condition in which they will readily give up their juice when they are subjected to the increased squeezing action of the following rolls.

I believe that the best results are obtained where the surface speed of one crushing roll is at least 5% greater than that of its mate or coacting roll, although I do not wish to limit myself unnecessarily in this respect. In any case it may be said that in the machine shown in Fig. 1, one of the crusher rolls has a surface speed substantially 10% greater than its mate, and one of the rolls of the mill B has a surface speed substantially 10% higher than that of a coacting roll. In the particular form shown in Fig. 1, the top crusher roll has a surface speed substantially 10% greater than that of the lower crusher roll, and the top roll 12 has a surface speed substantially 10% greater than that of its coacting lower roll 13. In this particular case also, the speed of roll 12 is the same as that of bagasse roll 14. It will be seen therefore that in the three-roll mill, as in the crusher, circumferentially grooved intermeshing upper and lower rolls have surface speeds which differ substantially from each other. I do not wish to limit myself, however, in all of these respects, as changes may be made in the details without departure from the principles involved.

In the case under discussion the two coacting crusher rolls 10 are of substantially the same diameter; and the three rolls of mill B are all of substantially the same diameter, which diameter will in practice be preferably but not necessarily slightly greater than the diameter of rolls 10. The differential motion to which I have referred may in such a case be obtained by the use of intermeshing gears on the roll shafts, having a dissimilar number of teeth. The gear 16, by which the upper roll 10 is driven, has a somewhat smaller number of teeth than its coacting gear 17, the difference in the number of teeth being so chosen as to bring about the relative roll speeds desired, the differ-

ence in this particular case being substantially 10%, as above stated. The lower roll 19 is driven by a shaft 18 on which gear 17 is mounted, the gear 16 being mounted on the shaft of the upper roll 10. The mill B is driven from a shaft 19 connected with or carrying the roll 12, and a gear 20 on said shaft meshes with a gear 21 on the shaft of cane roll 13 and with a gear 22 on the shaft of bagasse roll 14. In this particular case, the gear 21 has a larger number of teeth than the gears 20 and 22, such number being so chosen as to effect the drive of the top roll at a surface speed which is 10% higher than that of the cane roll 13.

The grooving of the rolls 20, 21 and 22 is shown in Fig. 4. These rolls are similar to those shown in my previous application, each being provided with a plurality of annular grooves, although in this case I have not shown the top roll 12 as provided with longitudinal grooves as in the former case. These longitudinal grooves may be employed, however, if desired, for increasing the hooking or drawing-in action on the cane and gripping the same while the cane passes through the bite of the rolls 12, 13, and then through the bite of the rolls 12, 14.

In the modified form shown in Fig. 3, the preliminary crusher A is the same as that previously described, but in the three-roll mill B', the cane roll 13^a, instead of being of substantially the same diameter as the other rolls of mill B' is of somewhat smaller diameter. It has, however, the same number of R. P. M., owing to the fact that in this case gears (not shown) having an even number of teeth are mounted on the shafts of rolls 12, 13^a and intermesh, in accordance with the usual practice. In this manner, as in the case previously described, the relative surface speed of the cane roll is decreased. In such a mill, also, the surface speed of the top roll is at least 5% greater than that of the cane roll and in this particular case the top roll surface speed is about 10% faster than the cane roll surface speed, as in the case previously described.

The operation of the grinding mill will be more or less obvious from the foregoing description. The difference in the surface speeds of the rolls at opposite sides of the cane stalk produces a sort of tearing motion on the stalk, which I term a friction motion, due to the fact that friction is exerted upon the stalk by one roll while it is being held by the coacting roll. In the particular forms shown, the cane is held back in a sense by the lower crusher roll while it is being acted upon frictionally and torn apart and shredded by the upper crusher roll. In the mill B or B', on the other hand, the top roll has a greater surface speed and while the stalks are held by the cane roll the top roll ribs tear them apart and shred them. In

this particular case the cane roll grooves are smaller than those of the top roll, as shown in Fig. 4, and the roll with the small grooves is the slower one. I do not limit myself, however, to such an arrangement, nor to a three-roll mill in which the top roll has a greater surface speed than another roll. Various changes in these and other respects may be made without departing from the scope of the invention as defined in the claims.

It will be understood that as a general rule the crusher rolls are provided with teeth and that the ribs of the upper and lower crusher roll are of the same pitch, corresponding somewhat to the top roll and bagasse roll of the three-roll mill, although usually the pitch is greater than in the case of these particular rolls of the three-roll mill. The cane roll is set farther apart from the top roll than is the bagasse roll, although the distance between the top roll and cane roll is usually somewhat less than the distance between the two crusher rolls. As the top roll and bagasse roll are set quite close together, they can exert a powerful squeezing action on the cane, and as the cane has been effectively shredded in the crusher and in the bite of the top roll and cane roll, the squeezing action in the close bite of the top roll and bagasse roll of the three-roll mill is very effective in extracting juice.

It is preferred to increase the surface speed of the top roll relatively to that of the cane roll, in the three-roll mill, on account of the tendency of the faster roll, i. e., top roll, to carry along the cane in the same general direction as the curvature of the upper surface of the turn plate, which thus cleans off the latter and prevents clogging. I do not limit myself, however, to this feature in all aspects of the invention. By providing a friction motion on the cane between the top roll and cane roll, the cane is better conditioned, by the resulting shredding effect, for the subsequent heavy squeezing action, produced by the top roll in combination with the closely set bagasse roll. It may be found advantageous in certain cases, however, to differentiate the surface speeds of the top roll and bagasse roll, respectively, for producing a shredding action which will be of value in the following mill; and in such a case, either the top roll or the bagasse roll may be the faster one. This surface speed difference, also, may be effected by dissimilar toothing of the gears or by difference in the roll diameters, as in the cases previously mentioned.

The crusher and the three-roll mill are provided with the usual or any preferred hydraulic pressure devices, which I have not considered it necessary to describe in detail, although they are shown in a general way in the drawing. Usually the pressure

between the top and bagasse rolls of the three-roll mill is greater than that between the rolls of the preliminary crusher. The pressure in the preliminary crusher may be, say, 250 tons, whereas that in the first three-roll mill may be, say, 375 tons.

I am aware that in prior three-roll mills, and possibly in preliminary crushers, there have been surface speed differences between circumferentially grooved intermeshing rolls caused by the uneven wearing of the roll surfaces, in certain instances, and in some few cases there have perhaps been differences of surface speed resulting from inaccuracy in manufacture or similar causes. In such cases, however, so far as I am advised, the surface speed difference between coacting rolls has not amounted to, say, more than one or two percent, usually less, and it has been produced unintentionally and not by dissimilar gear toothing or for the purpose of producing the slightly increased shredding effect which may be incidentally caused thereby; whereas, in my invention, an effective shredding action is brought about intentionally and the mill designed accordingly, and as the roll surfaces wear, the tendency is further to increase the intentional shredding effect, which has the advantages herein stated of increasing the extraction materially and increasing to a marked extent the efficiency of the mill.

Usually it is more convenient to have the two coacting crusher rolls of the same diameter and to drive them by gears having a dissimilar number of teeth as described, but it is obvious that in some cases the difference of surface speed might be obtained by differences of diameter of the crusher rolls, as explained in connection with the top and cane rolls of the three-roll mill of Fig. 3. Other changes in this and similar respects may be made without departing from the scope of the invention as defined in the claims.

What I claim is:

1. A cane mill having a top roll, a cane roll and a bagasse roll, all of said rolls being provided with annular grooves, the grooves of the top and bagasse rolls being of the same pitch but offset so that the ribs of one of said two rolls extend into the grooves of the other, and the grooves of the cane roll being finer than the grooves of the top and bagasse rolls, the top roll and bagasse roll being set closer to each other than to the cane roll, and means for driving the top roll and the bagasse roll at substantially greater surface speed than that of the cane roll, thereby effecting a frictional shredding action upon the cane passing between the top roll and the cane roll.

2. A cane mill having a top roll, a cane roll having annular grooves therein, a bagasse roll, the top roll and bagasse roll

4
having approximately the same surface speeds and being set closer to each other than the top roll is to the cane roll, and means for driving the cane roll at a surface speed substantially slower than that of the top and bagasse rolls, thereby effecting a frictional shredding action upon the cane passing between the top roll and the cane roll.

3. In a cane mill, moving shredding means adapted to have cane pass thereover, said means having a ribbed surface, the ridges

of said ribs extending in the direction of movement of said cane, and a pair of co-operating rolls having a greater surface speed than said shredding means and being adapted to drag cane over said ribbed surface, one of said rolls being adapted to press the cane against said ribs while being dragged thereover.

In witness whereof, I have hereunto set my hand on the 28th day of April, 1921.

FRANKLIN FARREL, JR.
